UNITED STATES PATENT OFFICE

JOHN LE B. ARBUCKLE, OF COLUMBUS, OHIO, ASSIGNOR OF ONE-THIRD TO HARRY H. SEMMES, OF WASHINGTON, DISTRICT OF COLUMBIA

AUXILIARY ARM

Application filed January 7, 1928. Serial No. 245,179.

This invention relates in general to supplementary firearms and more particularly has reference to an auxiliary rifle for shot guns.

5 Previous to this time rifles of this character have usually been mounted on the top or bottom of a gun barrel, so that either the sight on the supplementary rifle served for the aim of the gun, or the ordinary sight on the 10 gun served for the aim of the supplementary rifle as well. This has proved disadvantageous as different gauge shells and caliber cartridges cannot be accurately fired with the same sight setting.

15 An object of this invention is to provide a small bore or gauge auxiliary rifle or gun for large gauge or bore firearms.

Another object of this invention is to provide an auxiliary rifle or gun which may be 20 fitted on a firearm without interfering with the function of the weapon to which it is attached.

Another object of this invention is to provide an auxiliary rifle or gun that may be 25 easily and fixedly mounted on a firearm and readily detached.

Another object of this invention is to provide an auxiliary arm for hand weapons that may be accurately sighted without interfering 30 with the aim of the weapon upon which it is mounted.

A further object of this invention is to provide an improved breech mechanism for an auxiliary arm.

35 A still further object of this invention is to provide an auxiliary arm that may be conveniently carried apart from the weapon upon which it is intended to be mounted.

With these and other objects in view which 40 may be incident to my improvements, the invention consists in the parts and combinations to be hereinafter set forth and claimed, with the understanding that the several necessary elements comprising my invention, 45 may be varied in construction, proportions and arrangement, without departing from the spirit and scope of the appended claims.

In order to make my invention more clearly understood, I have shown in the accompanying drawings means for carrying the

same into practical effect, without limiting the improvements in their useful applications to the particular constructions, which for the purpose of explanation, have been made the subject of illustration.

55 In the drawings forming a part of this specification:

Figure 1 is a side elevational view showing the auxiliary rifle mounted on the side of a double barrel shot gun;

Fig. 2 is a top view of the weapons shown in Figure 1;

Fig. 3 is an elevation sectional view taken on lines 3—3 of Fig. 2;

Fig. 4 is a side elevation sectional view of 65 the breech mechanism shown in closed position;

Fig. 5 is a side elevation sectional view of the breech mechanism shown in open position;

Fig. 6 is a sectional view taken on line 6—6 of Fig. 4;

Fig. 7 is a perspective view of the extractor;

Fig. 8 is an elevation sectional view taken on line 8—8 of Fig. 4;

Fig. 9 is a bottom view of the breech mechanism;

Fig. 10 is a side elevation partly sectional view of the firing mechanism shown on half cock;

Fig. 11 is a side elevation partly sectional view of the firing mechanism shown on full cock;

Fig. 12 is a perspective view of the cocking piece;

Fig. 13 is a side elevational view showing the mounting of the rifle on a gun.

Referring by numerals to the drawings in which the same and similar elements are designated by like symbols of reference throughout, and more particularly to Figure 1, there is shown a shot gun comprising a plurality of barrels 1 and 2 adjacent a sighting rib 3, as shown in Figure 2.

The barrels are hinged on the pistol grip 5 of a stock 6, on a breech mechanism 4. A hand grip 7 is snapped on the bottom of the barrels 1 and 2 against the breech mechanism and the breech operated by a locking lever 8. The gun is fired by triggers 9 and 11, operated 100

by a safety catch 12, positioned on the top of the pistol grip 4 in the rear of the locking lever 8.

An auxiliary arm forming the subject matter of this invention, comprising a barrel 13, having a bore 14, as shown in Figure 3, is mounted on the side of the barrel 2 in approximately the same horizontal plane as that of the barrel, so that the line of sight is approximately parallel to the line of the sight of the gun. A plurality of tapered tongues 15 and 16 are brazed on the side of the barrel 13, designed to fit in oppositely disposed tapered lugs 17 and 18 brazed on the side of the gun barrel 2 to afford a mounting of the arm on the side of the gun. A cam 19 formed on the end of an arm 21 pivoted to the side of the barrel 13 by a pin 22, is adapted to fit against the rear mount and hold the barrel securely in position.

While the drawings show a small caliber rifle mounted on a double barrel shot gun, it is manifest that it may be attached to any other type of shot gun or that a small gauge shot gun may be substituted for the rifle for attachment on a high powered rifle.

The barrel 13 is formed with a boss 23 at the top of the butt to which there is pivoted a breech block 24 through lips 25 and 26 by a pin 27, as shown in Figures 5 and 6. A plurality of pins 28 and 29 are set in the outer face of the lips 25 and 26 below the pin 27 adapted to fit in grooves 31 and 32 cut in ears 33 and 34 formed on an extractor 35, as shown in Figure 7.

The extractor 35 is adapted to slide in a slot 36 cut in a mounting plate 37 formed integral with the bottom of the barrel 13. A plate 38 is fixed on the bottom of the mounting plate under the slot 36 by screws 39, and formed with a groove 41 upon which the extractor 35 is adapted to slide. When the breech block 24 is rotated around the pin 25, the pins 28 and 29 operate in the grooves 31 and 32, and force the extractor back in the slot 36 on the mounting plate in the groove 41.

A recess 42, concentric with the face of the barrel is cut in the breech to receive the rim of a cartridge and the bottom cut away to seat an extractor claw 43 formed integral with the extracting mechanism 35. A lip 44 is formed on the extractor claw adapted to fit against the bottom of the breech block 24, and retain the extracting mechanism in position when the breech is locked.

A firing pin 45 is mounted in an aperture 46 bored in the front of the breech block 24. A groove 47 is cut in the bottom of the firing pin 45 adapted to cooperate with a pin 48 fixed transversely across the aperture 46 and hold the firing pin in position.

A rod 49 threaded at both ends is mounted in the rear end of the breech block, adapted to engage a striker 51 and a cocking piece 52. A coil spring 53 is mounted between the

striker pin 51 and the rear of the breech block 24, so that when the rod 49 is drawn out and released, the striker 51 will contact with the firing pin 47 under the force exerted by the spring 53.

The cocking piece 52 is formed with a shank 54 terminating in an integral tapered locking plate 55. The shank 54 is adapted to pass through a slot 56 cut in the mounting plate 37, and the tapered edge of the locking plate engages the bottom of the mounting plate to fix the breech block in locked position.

A sear 57 is formed on the side of the cocking pieces 52, as shown in Figure 12. A trigger mechanism 58 is pivoted on the side of the breech block by a pin 59, having a toe 60 adapted to engage a half cock notch 61 and a full cock notch 62 formed on the sear. One end of a leaf spring 63 is mounted on the bottom of the sear by a screw 64, and the other end held by a pin 65 embedded in the side of the mounting plate 37. A boss 66 is formed on the side of the trigger mechanism to which is hinged a trigger 67 by a pin 68 so that it may be raised to an upright position when not in use as shown in Figure 8.

A slot 69 is cut through the mounting block adjacent the slot 56 to receive the locking plate 55 together with an adjoining slot 71 to receive the shank 54. When the cocking piece 52 is drawn back slightly past the position of half cock the locking plate may be raised through the slot 69 and the breech block rotated forward so that the extractor is forced back and a cartridge started from the chamber, where it may be withdrawn and another inserted.

The bevel surface on the locking plate 55 permits the breech block to be snapped shut and the gun carried at half cock without the possibility of the action swinging open at half cock. When the toe 60 of the sear registers in the full cock notch 62, the lever 67 is adapted to be pressed by the thumb, which may rest across the small of the stock 6 on the piston grip 5.

The rifle is attached to a side of the shot gun of either a single or double barrel type through the tapered tongues and grooves 15 and 17 and 16 and 18 and locked by the cam 19 where it may be readily removed by disengaging the cam. A rear sight 69 having a slot 71 is screwed on the top of the breech block by a screw 72 and a front sight 73 having a bead 74 is mounted on the muzzle of the barrel. If so desired a peep sight may be conveniently mounted on the breech block or on the end of the mounting plate 37.

The toe 60 is ordinarily allowed to rest in half cock position and when it is desired to cock the rifle the cocking piece is pulled back until the toe engages the full cock notch on the sear. The tapered plate 55 is disengaged from the mounting block through the slot 69, so that the breech block may be rotated for-

ward and a cartridge placed in the bore of the barrel with the rim against the extractor. When the breech block is closed the cartridge is shoved into the bore of the barrel until the 5 rim is seated in the recess in the bore.

When the block is closed the trigger is in half cock position and when it is desired to fire the weapon it is pulled back by the cocking piece, as previously stated, until the toe 10 60 registers with the full cock position on the sear where it may be fired by pressing the trigger 67.

There is accomplished by this invention an auxiliary rifle or gun for large bore guns or 15 high caliber rifles that may be easily and fixedly mounted on a firearm and accurately aimed without interfering with the sight of the weapon to which it is attached and readily detached and conveniently carried apart from 20 the weapon.

While I have shown and described the preferred embodiment of my invention, I wish it to be understood that I do not confine myself to the precise details of construction 25 herein set forth, by way of illustration, as it is apparent that many changes and variations may be made therein, by those skilled in the art, without departing from the spirit of the invention, or exceeding the scope of the ap- 30 pended claims.

I claim:

1. An auxiliary arm comprising a barrel and engaging means carried on the side thereof to longitudinally wedge in receiving 35 means associated with the side of the barrel of a hand weapon.

2. An auxiliary arm comprising a barrel having tapered tongues mounted thereon to longitudinally wedge grooves mounted on 40 the barrel of a hand weapon.

3. An auxiliary arm comprising a barrel having a plurality of tapered tongues mounted on the side thereof to longitudinally wedge in grooves mounted on the side of a 45 barrel of a hand weapon and means to lock the arm on the side of the weapon.

4. An auxiliary arm comprising a barrel having tapered tongues mounted thereon to longitudinally wedge in tapered grooves 50 mounted on a barrel of a hand weapon and a cam lever to lock the tongues in the grooves.

5. An auxiliary arm comprising a barrel having tapered tongues on the side at the muzzle and breech thereof to engage oppositely disposed grooves on the side of the barrel of a hand weapon and a cam pivotally mounted on the barrel of the auxiliary weapon to engage the tongue at the breech and lock the arm on the weapon.

6. An auxiliary arm comprising a barrel, a recess in the barrel to receive the rim of a cartridge, a mounting block fixed to the breech of the barrel, a breech block pivotally mounted above the mounting block, an ex- 65 tractor forming a portion of the recess in the

barrel to engage the rim of the cartridge and means operating on the mounting block, formed integral with the extractor cooperating with the breech block to eject the cartridge. 70

7. An auxiliary arm comprising a barrel, a mounting block fixed to the breech of the barrel, a breech block pivotally mounted above the mounting block, a firing pin operating in an aperture in the front of the breech block, a spring operated striker mounted in the rear of the breech block, and a cocking piece in engagement with the striker to lock the breech block on the mounting block. 75

8. An auxiliary arm comprising a barrel, a mounting block fixed to the breech of the barrel, a breech block pivotally mounted above the mounting block, a firing pin operating in an aperture in the front of the breech block, a spring operated striker mounted in the rear of the breech block, a cocking piece in engagement with the striker, a sear mounted on the breech block to engage the cocking piece and means to operate the sear. 80

9. An auxiliary arm comprising a barrel, means to receive the rim of a cartridge in the breech of the barrel, means to retain the cartridge in the barrel, means to lock the cartridge retaining means, means mounted in the front of the cartridge retaining means to fire the cartridge, means forming the locking means mounted in the rear of the cartridge retaining means to operate the firing means, means mounted on the cartridge retaining 100 means to fix the position of the firing operating means, means to release the fixing means and fire the cartridge, means forming a portion of the rim receiving means to cooperate with the cartridge retaining means 105 and extract the cartridge from the breech of the barrel, and means to mount the arm on a hand weapon.

10. An auxiliary arm comprising a barrel, a recess in the barrel to receive the rim of a cartridge, a mounting block fixed to the breech of the barrel, a breech block pivotally mounted above the mounting block, an extractor forming a portion of the recess in the barrel to engage the rim of a cartridge, a claw 110 formed integral with the extractor sliding on the mounting block and cooperating with the breech block to extract the bullet, a firing pin operating in an aperture in front of the breech block, a spring operated striker 115 mounted in the rear of the breech block, a cocking piece in engagement with the striker to lock the breech block on the mounting block, tapered tongues on the side of the barrel, tapered tongues on the side of the breech at the muzzle and breech to engage oppositely disposed grooves on the side of a 120 barrel of a hand weapon and a cam lever pivotally mounted on the barrel of the auxiliary weapon to engage the tongue at the breech and lock the arm on the weapon. 125

11. An auxiliary arm comprising, a barrel and means carried thereby to longitudinally wedge the same on a hand weapon substantially parallel to the barrel thereof.

5 12. An auxiliary arm comprising, a barrel, means carried thereby to longitudinally wedge the same in receiving portions associated with a hand weapon substantially parallel to the barrel thereof.

10 In testimony whereof I affix my signature.
JOHN LE B. ARBUCKLE.
